UNITED STATES PATENT OFFICE

2,372,892

PAPER FEEDING DEVICE

Ioino Ghertman, St. Mande, France, assignor to
 International Business Machines Corporation,
 New York, N. Y., a corporation of New York

Application August 6, 1941, Serial No. 405,699
 In France March 15, 1941

20 Claims. (Cl. 235—61.7)

This invention relates generally to accounting machines and more specifically to paper feeding devices for perforated card controlled tabulators.

An object of the invention is to provide a device of the kind referred to for automatically and simultaneously printing various forms of receipts, accounts, invoices, statements, etc., comprising sheets of a given size which may have printed thereon a variable number of items.

The paper feeding device usually mounted on tabulating machines is generally of the kind disclosed in the United States Patent 2,310,418.

With the device of the known type, it is necessary twice to feed the cards through the tabulator for printing recapitulative forms as statements, viz., first, for receipts, invoices or accounts having printed thereon elementary operations, and second, for statements which recapitulate said elementary operations. There is a certain risk of errors by substitution of cards, as well as of errors due to the machine, by reason of the risk of errors pertaining to this operation being multiplied by repeating said operation. It is therefore an object of the invention to provide a device for simultaneously feeding a plurality of record strips or sheets through a common printing system to produce by a single printing operation of the tabulating machine one original print and one or several duplicates, said device comprising improvements to a paper feeding device of the known type and its combination with a general means disclosed in the United States Patent 1,957,203.

Another object of the invention is the provision of a device for simultaneously printing statements and accounts to avoid errors of the kind referred to, as well as to save time.

A further object of the invention is to provide a device of the kind referred to, which comprises the combination of a tabulator platen roller having mounted thereon said device with a paper feeding roller adapted to cooperate with an intermediate carbon paper which is inserted between a first paper sheet or strip having printed thereon recapitulative forms as, e. g., statements, and a second strip having printed thereon forms as, e. g., accounts, said carbon paper being fed by frictional engagement thereof between the account sheet and the statement sheet.

Still a further object of the invention is to provide a combination of the kind referred to, wherein said account sheet comprises a back carbon paper sheet, thus avoiding a special intermediate carbon paper.

A further object of the invention is the provision of a counter feed roller loosely journaled in its bearings and adapted to be selectively connected by a switch means comprising an oscillating pinion carrier to said other paper feed roller or to said platen roller of the tabulating machine. Said counter feed roller serves for a double purpose:

(a) It permits printing of duplicates of each statement or of each account by feeding of a paper strip arranged between the statement sheet and the account sheet, and by selectively cooperating through intermediate carbon papers with either of said sheets as it is connected to said platen roller or to said account sheet feeding roller.

Thus feeding of the paper sheet which will constitute an account duplicate or a statement duplicate, which sheet will be called hereinafter "the duplicate," occurs regardless of feeding of the statement sheet or of the account sheet, and therefore feeding of said duplicate will not affect feeding and positioning of said statement sheet or account sheet.

(b) When the counter feed roller is positively connected to the platen roller, it may be adapted to feed a part of said record strips rolling on said platen roller to reduce the variations of line spaces due to discrepancy between the speed of linear feeding, said discrepancy being in turn due to the variations of distance of said record strips relatively to the platen roller axis. Said discrepancy of speed may be avoided by suitably distributing the paper sheets between the platen roller and the counter feed roller which both are adapted to drive the paper and to rotate, in this case, at the same speed.

Another object of the invention is to provide paper sheet driving means comprising small friction rollers positively connected to the different feed rollers and spring means adapted to cause said friction rollers to operatively engage the surface of said feed rollers to avoid any slip of said paper sheets relatively to the roller surfaces.

A further object of the invention is to provide a variable pitch record strip feeding mechanism having incorporated therein a line by line spacing device.

Still a further object of the invention is to provide a line by line spacing device incorporated to said paper feeding mechanism and comprising, in combination, a brake, a stop lever, a line space setting means and an eccentric notch disc adapted to impart to said line space control

means a feed movement, said movement being slow whilst starting and at the end thereof, but rapid between the starting and the end thereof, for avoiding the abutment member which has been employed heretofore in known line spacing devices to obtain correct positioning of the sheet.

Another important feature of the invention comprises a paper feeding mechanism adapted to be selectively connected to either the account sheet feed roller or to the platen roller for driving the statement sheet, by means of a differential device adapted to selectively switch the paper feed motor drive on either said account sheet feeding roller or on said platen roller, switching being effected by electromagnetic means cooperating with switches or contacts the closing of which may be effected by electromechanical means as by cam members or by brushes operatively engaging contact plates through a marginal series of longitudinally spaced perforations in said account sheet and statement sheet.

Another object of the invention is the provision of a free wheel platen roller device comprising, in combination, a first pawl rigid with said platen roller and a second pawl rigid with a gear positively connected to said differential device, said pawls being arranged in such a manner that driving of said platen roller by the line by line spacing device of the tabulating machine will not drive the gears of said differential device.

A further object of the invention is to provide a safety device comprising electromagnetic means and adapted to prevent said paper feeding device of the tabulating machine from driving said platen roller when the ordinary line by line spacing device of the tabulator operates simultaneously with said paper feeding device.

Still a further object of the invention is to provide a paper feeding device of the kind referred to, in which the carbon paper rollers are adapted to be driven by said platen roller with speed reduction for slowing down the feed of said carbon papers to reduce consumption of the latter.

Another object of the invention is the provision of electric means for controlling the paper feed motor speed, wherein control is ensured by the combination of a pair of relays, the first relay being actuated by the automatic control change of the tabulating machine, and the second relay being actuated by a plurality of brushes adapted to analyse said perforations in said statement sheet and account sheet to detect the regions of said sheets wherefrom the motor speed is to be reduced or increased. Said motor speed control has for its purpose to ensure correct positioning of the sheet for printing, regardless of the pitch of feed.

A further object of the invention is to provide record strips of different width for printing some items on both the account sheet and statement sheet, whilst printing other items on one sheet only, as, for instance, to avoid printing on the account forms of progressive totals which shall appear only on the statement forms.

Still a further object of the invention is the provision of a plurality of suitably arranged brushes adapted to cooperate with said paper sheet perforations to control the movement of the last line of the account form or statement form through the printing line, said brushes forming a part of a control mechanism adapted to detect a statement form approaching its end whilst printing of the last line of an account.

Another object of the invention is to provide a novel electromechanical device adapted, first, to feed the account sheet (which moves faster than the statement sheet) by means of either the ordinary paper spacing device of the tabulator or the paper feeding mechanisms of the device disclosed in this specification, the feed pitch being variable from a first line of data to any desired point of a form as, e. g., to the first line of the next form, and second, to feed the statement sheet by either one or several line spaces or by a variable pitch which may terminate on the first line of the next statement form, said movements being effected by said paper feeding device. To stop the paper sheet in any desired point of each form and to permit printing of given data on the desired point of said form, there are employed perforations punched out from the paper sheets in the left and/or right edge portions thereof, said perforations being adapted to permit completion of electric circuits by means of suitably arranged brushes cooperating with contact plates having sliding thereon said paper sheets; a disengaging electromagnet of said paper feeding mechanism is energized upon completion of said circuit to stop said paper sheet (statement form or account form).

A further object of the invention is the provision of a paper feeding device of the kind referred to, wherein the feeding mechanism is started by means of a starting electromagnet adapted to be energized in a known manner upon different other operations as printing of a line of data in a listing operation, printing of a total in a tabulating operation, operation of the automatic control of the tabulator, printing of a progressive total, etc.

Some of the principal operations which may be carried out by means of the device forming the subject matter of the invention will now be described.

1. When statements are to be printed simultaneously with receipts, i. e., with forms having printed thereon a single line of items, each receipt is automatically fed, immediately after the stroke of the tabulator type bars, to move under the control of the device disclosed in this specification with a pitch great enough to bring the item line of the next receipt in printing position, while the statement sheet is fed ad lib. by one or two line spaces.

2. By means of the brushes which detect the end of each statement, the device of this invention is adapted to feed first the receipt sheet by means of the paper feeding mechanism which feeds said sheet to bring the item line of the next receipt in printing position, and then the statement sheet from the last line of said statement to the first line of the next statement which is thus brought into printing position by means of the paper feeding mechanism which has previously fed the receipt sheet.

3. When statements are to be printed simultaneously with invoices or accounts, i. e. with forms having printed thereon a plurality of item lines, the paper feed, instead of occurring after printing of each line, occurs after printing of a number of item lines spaced from each other by one or two line spaces, and more generally after printing of the total of the invoice or account.

4. The device of this invention is adapted to cause feeding of the account sheet to print the total on a given location of each form, regardless of the number of item lines printed on each form, and then to feed the account sheet from the total

printing line to the first line of the following account. In turn the statement is always fed by one line space after printing of one line of the account, regardless of the line space between the lines of the account.

5. Furthermore, the device disclosed in this specification permits controlling, by means of the printings on a receipt or account form, of feed of the corresponding statement form to ensure printing of the first line of the next statement form. In fact it might be possible that the last line of a statement form be not printed simultaneously with the last line of an account form. In this case, it will be advantageous to avoid printing of a part of the account on one statement form and printing of the other part of the same account on another statement form. This is ensured by the control mechanism adapted to detect a statement form approaching its end whilst printing of the last line of said account.

By means of this operation, when the paper length available on the statement form is greater than the length available on the account form, in printing the last line of said account form it is only the latter which is fed by the paper feeding mechanism to bring the first line of the following account into printing position, the statement remaining in place after a feed of one or two line spaces for having printed thereon the item lines of the next account.

On the other hand, when the statement length available is smaller than the account length available, in printing the last line of said account the statement form is fed automatically after feeding of said account to bring the first line of the next statement form into printing position.

6. The device of this invention permits printing of a progressive total at the end of one statement and at the head of the following statement when the item lines to be printed extend to a greater length than that of the statement. Two cases are possible:

(a) The account form is of the same width as the statement form. In this case, when the statement form approaches its end, the account form is fed automatically to bring the first line of the following account into printing position; in this moment the progressive total is printed, and said printing is followed by the feed of the statement form to bring the first line of the following statement form into printing position. In this moment occurs another printing of the progressive total, so that the progressive total is printed twice on the following account. The latter is fed again to bring the first line of the next account into printing position. Then the printing operation begins again simultaneously on the account sheet and on the statement sheet. It will be seen that in this case the account form having printed thereon twice the progressive total can not be employed and will be lost, but that by reason of the loss of this form the progressive total will be printed only on the statement form and does not appear on the accounts with the items of which it might interfere.

(b) The statement form is of a greater width than the account form. In this case, the surplus of width of the statement form is intended for printing of a progressive total to avoid the loss of a form. Operation occurs in the following manner: As the last line of the statement is printed without any change of the indicator number of the perforated card group put into the tabulator, the account sheet is fed automatically to bring the first line of the next account into print-

ing position. The progressive total is now printed on the portion of said statement sheet which exceeds the account sheet, and this operation is followed by feeding of the statement sheet to bring the first line of the next statement form into printing position.

In this moment occurs the second printing of the progressive total, which printing is also effected on the portion of the statement sheet which exceeds the account sheet, and the printing operation begins again on the second sheet. In this manner both progressive totals, whilst being printed on the statement sheet, are not printed on the account forms.

- 15 7. The device disclosed in this specification permits to carry out an operation which has been obtained heretofore, in some accounting machines, by means of a special mechanism, whilst employing record strips of any width, the latter being only limited by the total width of the platen roller. The advantage thus provided will be readily seen, for when mounting a mechanism of the aforementioned kind on a tabulating machine, the platen roller must be divided into a pair of parts, one part being fed line by line after each printing, and the other part being fed by a variable pitch under the control of a carrier device. It results from the preceding that the width of the record strips must not exceed the half of the total width of the platen roller. Thus the device of this invention enlarges the capacity of the record strips, i. e. of the forms adapted to be printed by the machine, to substantially twice the amount provided heretofore.
- 30 8. Finally, the device disclosed in this specification comprises a line spacing mechanism which provides an adjustable number of line spaces for each cycle of passage of cards through the tabulating machine, which mechanism cooperates with the ordinary tabulator line spacing device comprising generally one, two or four line spaces per cycle of passage of cards, thus permitting to obtain a different line space on the original and on the duplicate.
- 45 45. The foregoing and other objects of the invention will become apparent as this specification continues with reference to the drawings forming part of the disclosure.

- In the drawings:
- 50 Fig. 1 is a diagrammatic perspective view of the device of the invention.
- Fig. 1a is a diagrammatic side elevational view showing the engagement of the different sheets in the roller carriage.
- 55 Fig. 2 is a front elevational view of the different supporting means (guide-plate, contact plates, brush carrier and auxiliary supports) of the device of the invention.
- Fig. 3 is a longitudinal vertical sectional view of the same device, taken on line III—III of Fig. 4.
- 60 Fig. 4 is a longitudinal horizontal sectional view of the aforesaid devices, taken on line IV—IV of Fig. 3.
- 65 Fig. 5 is a front elevational view of the device of the invention incorporated in an alphabetic and numeric printing tabulating machine, illustrating the assembly of the paper feeding mechanism and its motor drive with the differential device which selectively switches the movement to either the account sheet feed roller or the platen roller.
- Fig. 6 is an enlarged front elevational view, some parts of the roller carriage being broken away.

Fig. 7 is an enlarged side elevational view of the roller carriage of Fig. 6, seen in the direction of the arrows VII—VII of Fig. 6.

Fig. 13 is a sectional view taken on line XIII—XIII of Fig. 14.

Fig. 14 is a side elevational view of the feeding mechanism of the device of the invention, some parts being broken away.

Fig. 15 is a front elevational view, partly in section, of the mechanism shown in Fig. 14, some parts being broken away.

Figs. 16 to 19 inclusive are intended to be joined by lines X₁, Y₁; X₂, Y₂; X₃, Y₃, to form the general wiring diagram of the device of the invention and to illustrate the chief connexions thereof with the tabulating machine having incorporated therein said device.

Figs. 20 to 23 inclusive are intended to be joined by lines X₁, Z₁; X₂, Z₂; X₃, Z₃, to form a modified wiring diagram for providing printing of progressive totals simultaneously on the statement sheet and on the account sheet.

Figs. 24 to 35 inclusive show sample sheets of the various record forms which may be produced under control of the devices of the invention.

The following part of this specification refers to an alphabetic and numeric printing tabulating machine of the kind disclosed more particularly in United States Patents Nos. 1,957,203 and 2,042,392, and in United States patent applications Serial Nos. 455,279 (filed May 24, 1930), 534,583 (filed May 2, 1931), 520,506 (filed March 6, 1931), 634,690 (filed September 24, 1932), 49,687 (filed November 14, 1935), and 89,277 and 89,283 (both filed July 7, 1936) all of said applications corresponding, respectively, to Patents 1,944,667, 2,056,363, 1,909,549, 2,016,682, 2,165,288, 2,131,918, and 2,150,218.

It is to be understood that the device of the invention may be modified in details as, e. g., in the fixing method of the mechanism to be adapted to any other machine as a numeric tabulator, a typewriter, any keyboard controlled machine and, more generally, any machine for printing forms as invoices, accounts, receipts, statements, term notifications, day-book leaves, etc.

It will be remembered that an alphabetic and numeric printing tabulating machine of the aforementioned type is adapted to be controlled by cards which comprise perforations representing the alphabetic and numeric data.

Said cards are analysed by the brushes of the tabulating machine through the medium of which they control the totalizer and printing mechanisms of said tabulating machine. These cards are arranged in groups according to group numbers perforated therein so that a series of related items may be added to form a total amount of the group.

The cards are passed through the machine in succession under the brushes which are arranged

in upper and lower brushes, and automatic group control devices compare the group numbers on consecutive cards so that a group change may be detected. When such a change is detected, a total printing operation is initiated and the totalizer or accumulator is reset. As items are listed, a line spacing device is operated after each impression to space a record strip which passes on the platen roller of the tabulator and on which are printed the card data or the accumulator totals.

The record forms may be of the type disclosed in the aforesaid United States Patent 2,310,418, and preferably comprise a strip which is unfolded out of a magazine, passed around the platen roller and then returned to a receiving magazine. A marginal perforation is provided on each side of said paper sheets with a predetermined pitch which preferably corresponds to the length of the forms comprising the unfolded elements. Said perforations are adapted to control stopping and feeding of the record strips upon detection of an invoice end or an account end, as well as of a receipt end or a statement end; they are also adapted to control certain operations as printing of a total, starting of the card analyser mechanism, etc.

When mounting the device of this invention on an alphabetic and numeric tabulating machine of the aforesaid kind, there will be employed record strips similar to those indicated hereabove.

In the preferred form of the invention, there are employed a pair of record strips, viz, the account strip 1 and the statement strip 2 (Figs. 1 and 1a).

It is to be understood that there might be employed a plurality of record strips. The account sheet and the statement sheet respectively pass on contact plates p₁ and p₂ (which form also adjustable space guides for the paper, and are shown in the diagrammatic view of Fig. 1, as well as in Figs. 2 and 4) and under a plurality of analyzing brushes b₁, b₁' and b₂, b₂' (Fig. 1) adapted to complete electric circuits upon frictional engagement thereof with the contact plate surface through a series of perforations c₁, c₁' and c₂, c₂' respectively provided in each marginal portion of said record strips 1 and 2 respectively. Said strips are now driven into a three roller carriage mounted on the tabulating machine by means of a support member 3 (Fig. 7). Said carriage is free for lateral displacement on a pair of guide rails 4. In said carriage, the lowermost roller 5 is the platen roller of the tabulating machine. Simultaneous printing of the statement and the account is effected by cooperation of said roller with the uppermost feeding roller 24 adapted to feed the account sheet 1, and the platen roller is adapted to drive the statement sheet 2 in the direction of the arrow shown in Fig. 1. While printing of the account sheet is effected by means of the inking ribbon r of the tabulator, printing of the statement sheet is effected through an intermediate carbon paper c supported by a carbon paper roller 120.

A paper feeding mechanism E_p similar to the paper feeding mechanism disclosed in the United States Patent 2,310,418 from which it differs by an additional paper spacing device e adapted to feed the paper line by line to one or a plurality of line spaces, permits transmitting of the movement of a motor M to either the uppermost roller 24 or the platen roller 5 through a differential device D₁ for selectively switching the drive to said rollers 24 and 5.

The platen roller 5 may be connected too, in a manner to be described hereinafter, to the ordinary paper spacing device of the tabulator, through a drive which is diagrammatically indicated by a chain in Fig. 1.

On the other hand, an intermediate roller 19 loosely journaled in its bearings is adapted to provide duplicates of either the statement or the account as it is operatively connected to either the uppermost roller 24 or the platen roller 5 by means of an oscillating pinion carrier 25. The duplicate d on which is to be printed the statement copy or the account copy is driven by roller 19 and supported by a guide plate p3. Said duplicate is printed through an additional carbon paper c' coiled on a carbon paper carrying roller 125 and inserted between said account sheet 1 and said duplicate d, the intermediate carbon paper c being inserted between the duplicate d and the statement sheet 2, as is shown in Fig. 1a.

In fact, driving of said record sheets and duplicate is effected through small friction rollers 7 associated to each of said rollers and arranged in a manner to be described hereinafter with reference to the driving method of said platen roller.

A number of auxiliary metallic supporting members s1, s2, s3 visible more particularly in Figs. 1, 1a, 2 and 3 are adapted to receive said record sheets, duplicates and intermediate carbon papers for returning thereof to the receiving magazines provided on the output side of the device of this invention.

Each of the essential features of said device will be described hereinafter in a more detailed manner.

Platen roller.—The platen roller 5 assumes the following functions:

1. It effects feeding of the statement sheet line by line, by one or two line spaces after printing of each item line, spacing being controlled by the ordinary line by line spacing device of the tabulating machine through the carriage lever 6 of said tabulating machine, which lever is shown in Fig. 8.

2. It feeds the statement sheet by a variable pitch, as after printing of the last line of a statement, upon a group number change or after printing of a total, feeding being stopped when the first line of the next statement form comes in printing position.

Said paper feeding is a more rapid one than the aforesaid feeding, the roller being connected, through a differential device to be described later on, to the paper feeding mechanism when the statement sheet is to be fed by a variable pitch which is greater than one or two line spaces.

It results from the preceding that the platen roller 5 is adapted to feed the statement sheet line by line by means of the ordinary line spacing device of the tabulator, or to provide a variable pitch feed by automatic connection thereof to said mechanism E_p adapted to feed the paper by a variable pitch.

There may be obtained by means of said roller the same operation as is effected by the aforementioned device disclosed in United States Patent 2,310,418.

Another feature of said roller, as well as of both said other rollers, consists, as has been shown, in the method of driving the paper sheets which are pulled by means of the friction rollers 7 instead of being pushed as in ordinary tabulator carriages.

Referring now to Figs. 6 and 7, each of said friction rollers comprises a pair of rubber wash-

ers 8 fixedly secured to a shaft 9 which supports a gear 10 meshing with a gear 11 adapted to slide in a lateral direction on a roller carrying shaft 12 positively driven by said platen roller 5 through gears 13, 14 and 15, gear 13 being keyed to shaft 12 and gear 15 being keyed to shaft of roller 5.

Thus any rotation of roller 5, regardless of its being controlled by the tabulator spacing device or by the paper feeding mechanism, is associated with a rotation of the driving friction rollers 7, this latter rotation being effected with the same circumferential speed as that of roller 5, thereby to limit any slip of the paper sheet.

It will be observed that said washers 8 are caused to engage the rubber surface of said roller 5 by a pair of springs 16 which engage by one end a fixed stem 17 and by the other end said shaft 9, by being coiled around assembling sleeves 18 rigid with jaws 20 supporting said shaft 9.

By means of this arrangement it is possible to manually pivot the friction roller system about the roller carrying shaft 12 for lateral displacement thereof to readily put in the paper sheet.

Counter roller.—The intermediate or counter roller comprises a rubber roller 19 which is adapted to cooperate in a manner similar to roller 5, with driving friction rollers 7.

The shaft of said roller 19 has fixedly secured thereto a pinion 21 which is operatively connected, by meshing with a gear 22 (Fig. 7), to a gear 23 adapted to rotate said roller carrying shaft 12.

Switch device.—It is an essential feature of the counter roller that it is adapted to be selectively driven by either the lower roller 5 or the upper roller 24 through a commutator or switch device comprising an oscillating pinion carrying plate 25 shown by a grey shade in Figures 6 and 7. Said plate is fulcrumed about the pivot screw 26, and has loosely journaled in each end portion thereof one pinion 27 mounted for idling on its axle stem 28.

Said plate 25 is furthermore provided at each of its ends with stems 30 engaging the side frame 31 through a spring 32, said stems 30 being simultaneously guided by slide holes in said plate 25 and by U-shaped members 33 fixedly secured, as by screws, to the plate 25.

A series of holes in said side frame 31 are arranged to register with the positions of said stems 30 according to the position of plate 25. When said stems are urged by said springs 32 to move into said holes, plate 25 is rigidly connected to side frame 31. By means of said arrangement of holes, said plate 25 is adapted to be brought into a pair of different positions by rotation thereof about said pivot screw 26.

In the first position of the plate 25 in Fig. 7, pinion 27 journaled in the upper portion of said plate meshes simultaneously with a gear 34 keyed on the shaft of roller 24 and with said gear 23, thus operatively connecting the counter roller 19 with the upper roller 24.

In the second position, the counter roller 19 is operatively connected, by means of said plate 25, with the lower roller 5; plate 25 is brought into this latter position by simply pulling the pair of stems 30 to disengage them from the side frame 31, thereby disengaging plate 25 from said side frame 31.

When the plate 25 is disengaged, it may be pivoted about the pivot screw 26 in a clockwise rotation until the lower pinion 27 meshes simultaneously with gears 21 and 13, thereby operatively

connecting roller 19 with roller 5 through the gears 13, 14 and 15.

When the plate 25 is brought into this other position, the stems 38 are disengaged and are caused by the springs 32 to move into the registering holes in the side frame 31; thus, the plate 25 is stopped by being rigidly connected to the side frame 31 to maintain meshing of pinion 27 with pinions 13 and 21, thus to permit printing of a statement duplicate.

Upper feed roller.—Referring now to Fig. 5, the upper feed roller 24 is connected through the differential device D₁ to the paper feeding mechanism E_p. The roller is connected with the differential device through a gear 35, Fig. 1, rigid with the roller shaft and arranged on the end opposite to gear 34. Roller 24 is adapted to feed the account sheet, in a similar manner as the other rollers, by means of a pinion 36 driving a pinion 13 keyed on the friction roller carrying shaft 12.

It results from this arrangement that the upper roller is adapted to be driven by the only paper feed mechanism E_p and to be rotated by a variable angle for feeding of the record sheet by a variable pitch. Said roller is also adapted, by means of the paper spacing device e incorporated in the mechanism E_p, to feed the account sheet by one or several line spaces.

Paper feeding mechanism E_p.—The paper feeding mechanism E_p shown in Figures 5 and 13 to 15 inclusive forms a unit mounted on a bracket 37 shown in Fig. 5. Said bracket is in turn secured to a flange 38 of the frame 39 of the alphabetic and numeric tabulator by means of a number of bolts 40.

The bracket 37 has also mounted thereon the motor M fixedly secured by screws 41 and rubber pads 42.

The shaft 43 of motor M is rigid with a worm 44 meshing with a worm gear 45 included in a housing 46 which is fixedly secured to a side frame 47 of the paper feeding mechanism E_p by means of brackets 48 and screws 49.

The motor M is adapted to drive the paper feeding mechanism by means of a shaft 50 having keyed thereon said worm gear 45. Said shaft 50 is journaled in a bronze sleeve 51 secured to the side plate 47 by screws 52. A gear 53 keyed on the shaft 50 meshes with a gear 54 mounted for idling on the shaft 55 (Fig. 14). The gear 54 is adapted to rotate the shaft 55 by means of the motor M upon engagement of a clutch comprising a first member 56 rigid with the gear 54 and a second member 56' rigid with the shaft 55 in the direction of rotation but free to slide thereon axially, said second member 56' being urged by a spring 57 towards said first member 56.

It will be noted that engagement of the clutch members 56, 56' is controlled by a clutch electromagnet E_m which is adapted to move, by attracting of its associated armature 63 upon energization, a lever 64 visible in Fig. 14. Displacement of said lever in the opposite direction is ensured by the attraction of the armature 65 of a disengaging electromagnet D_b upon energization of the latter. In this state, the shaft 62 is not driven by the motor M and the differential device D₁ is not controlled, thereby ensuring stopping of the upper roller or of the platen roller according to the setting of the differential device to switch the drive on either one or the other of said rollers.

Upon engaging of 56 and 56', movement is transmitted to said shaft 62 through the gear 58 keyed to the shaft 55, the gear 59 loosely mounted

on its axle 60 and the pinion 61 rigid with the shaft 62. The latter is connected to the differential device D₁ through an Oldham knuckle joint J (one member of this joint being represented in Fig. 15) so that when said differential device switches the drive on the upper roller in a manner to be described hereinafter, the upper roller 24 is free to be rotated by the motor M for feeding the paper by a variable pitch.

10 *Line by line spacing device of the paper feeding mechanism.*—The paper feeding mechanism has incorporated thereto a paper spacing device e which is also adapted to be controlled by the motor M in the following manner: Gear 53 is continuously rotated by motor M and drives gear 54 controlling the paper feeding mechanism and also a gear 66 keyed on a shaft 67. Said shaft has keyed to the other end thereof a pinion 68 adapted to drive a gear 69 loosely mounted on a stem 70 and rigid with a ratchet wheel 71. Thus said ratchet wheel 71 is continuously rotated, as well as gear 53, by motor M.

The stem 70 has loosely mounted thereon a notch disc 72 carrying a pin 73 having pivotally connected thereto a pawl 74 which has downwardly extending therefrom a projecting lug adapted to engage, in normal position, the armature 75 of a spacing control electromagnet 76. A lug on the opposite end of said pawl 74 is urged by a spring 77 into engagement of the pawl 74 with the teeth of said ratchet wheel 71.

When the armature 75 is in the position shown in Fig. 14, i. e., when it is not attracted by the electromagnet 76, pawl 74 is disengaged from 35 ratchet wheel 71, said armature forming an abutment for the lower projection of said pawl. When electromagnet 76 is energized, armature 75 is attracted and disengages pawl 74 which is now caused by spring 77 to operatively engage said 40 ratchet wheel 71. The ratchet wheel 71 is now adapted to drive the pawl and the notch disc 72 through the stem 73. Said disc 72 makes one complete revolution, after which it is stopped by the lower projection of pawl 74 abutting the edge 45 of armature 75 which has come back into its initial position by reason of the energizing circuit of the electromagnet 76 being interrupted. On the other hand, when the electromagnet 76 is again energized, it attracts its armature 75 to 50 move out from the path of pawl 74 at the end of the first revolution of the notch disc 72. Thus said notch disc may rotate by a second revolution, to be stopped in the same manner as hereinbefore described. It will be seen that the number 55 of revolutions of the notch disc 72 may be controlled by the time of energizing of the electromagnet 76.

The counterclockwise rotation of the notch disc is transmitted to the shaft 62 by means of a link 60 78 pivotally connected at one end thereof to a pin 79 rigid with the notch disc 72 and at the other end to a pin 80 secured on a crank 81 which has secured to the upper portion thereof a pin 82 pivotally supporting a pawl 83 which is urged 65 by a spring 84 into engagement with a ratchet wheel 85 rigid with the shaft 62. When the notch disc 72 rotates in a counterclockwise direction, the angular displacement of the pawl 83 in a clockwise direction is maximum when the ratchet wheel 85 has made a half revolution. During the second half revolution of the ratchet wheel 85 said pawl 83 comes back to its rest position, being disengaged from the ratchet wheel by reason of a pin 88 secured to said pawl 60 engaging a boss 86 of a cam disc 87. Therefore it

will be seen that the notch disc 72 is adapted to provide by rotation of the shaft 62 feeding of the account sheet by one or several line spaces through said differential device D₁ which switches, in this case, the drive on the upper roller 24.

A novel feature of the spacing device e consists in the fact that, by reason of employing a crank-and-link gear, the feeding movement of the pawl 83 is a very slow one whilst starting, then more rapid and finally slowed down again when the notch disc 72 has turned to an angle approximating 180 degrees. The return movement of said pawl 83 is effected in a similar manner. An advantage of this improvement consists in avoiding the abutment member which has been generally employed heretofore in known line by line spacing devices for the pawl 83 to obtain correct positioning of the sheet, line spacing being rough in known devices, and the absence of any abutment causing irregularity of spacing, which is avoided by the improvement provided by the invention.

Another novel feature of the device e consists in the fact that there has been provided a ratchet wheel 89 rigid with the shaft 62 and engaged by the pin 90 of a lever 91 fulcrumed on a pivot pin 92 and urged by a spring 93 into engagement with the teeth of said ratchet wheel 89. The system comprising said ratchet wheel 89 and lever 91 provides a brake for stopping shaft 62 and permitting correct positioning of line space. On the other hand, a stop lever 94 pivotally mounted on a pin 95 and caused by a spring 96 to engage the notch disc 72 serves to stop said notch disc by engagement of the free end of said lever with said notch to avoid any jump at the end of movement.

Finally, there has been provided an original device for passing from simple to double line space: The cam disc 87 has fixedly secured thereto a bent lever 97 which has in turn riveted thereto a small bracket 98. A rod 99 passes through the lever 97 and the bracket 98 which provides a guide member, said rod being adapted to move into a bore in a bracket 100 shown in Fig. 15 and secured to one of the side frames of the mechanism E_p. Thus the rod 99 is adapted to rigidly connect the cam disc 87 to the bracket 100. By lifting the rod 99 and compressing the recall spring 101, said cam disc 87 may be disengaged from said bracket 100, and the system comprising said disc and lever 97 may be moved forward or backward with regard to the plane of Fig. 15.

In the preferred form of embodiment, two different positions are considered:

1. By clockwise rotating the cam disc 87 about the shaft 62 in Fig. 14, the boss 88 of disc 87 which is to be engaged by the pin 88 of the pawl 83 is brought into its extreme right-hand position. In this position, when the pawl 83 is recalled back by crank 81, link 78 and notch disc 72, the pawl pin 88 will engage sooner the boss 88 than when the system comprising the disc 87 and the lever 97 is in the extreme left-hand position, and the shaft 62 is turned by an angle corresponding to one line space after each energization of the electromagnet 76.

2. When the system comprising the disc 87 and the lever 97 is in its extreme left-hand position, which is the position shown in the drawings, each energization of the electromagnet 76 causes the shaft 62 to be rotated by an angle corresponding to a double line space. In this circumstance, the upper roller 24 or the lower roller 5, according to the adjustment of the differential device D₁, pro-

vide feeding of the account sheet or statement sheet by a double line space.

Differential device D₁.—Referring now to Figs. 8 to 12 inclusive, the differential device D₁ is adapted to be driven by a shaft 62' connected to the shaft 62 through the Oldham joint J. The differential device D₁ is positively connected through gear systems to the upper roller 24 and to the platen roller 5.

10 The gears which connect the upper roller 24 to the differential device are: gear 105, gear 102 and gear 103 meshing with a pinion 104 idling on the shaft 62'. A pair of planet wheels 105 and 106 meshing with each other are mounted on both sides of a gear 107 on pins journaled in U-shaped brackets 107' secured to said gear. The planet wheel carrier gear 107 is loosely mounted on the shaft 62'. The planet wheel 105 meshes with a pinion 108 keyed to the shaft 62', and the planet wheel 106 meshes with the aforesaid pinion 104.

15 The differential device is connected to the platen roller 5 through the planet wheel carrier gear 107 which meshes with a gear 109 meshing with a gear 110 which cooperates with a ratchet wheel 111 rigid with the shaft of the platen roller 5 and adapted to be driven by said gear 110 through a pawl 112 mounted on said gear and urged into engagement with said ratchet wheel by a spring 113. The system comprising the ratchet wheel 111 and the pawl 112 with its spring 113 acts as a free wheel device adapted to drive the platen roller 5 through the differential device but preventing any rotation of the gear 110 and its associated gears when the ordinary line spacing device of the tabulator drives the platen roller 5.

20 Switching of movement on the roller 5 or on the roller 24 is effected by means of an anchor A₁ pivotally mounted on a pin a and comprising a pair of axially spaced arms 114 and 115 including a suitable angle so that said anchor be adapted upon control of the armature 116 of an electromagnet 117 to selectively engage either the gear 107 which forms a planet wheel carrier or the pinion 104 to stop thereby said gear or pinion. 25 Upon completion of the energizing circuit of the electromagnet 117, armature 116 engages the poles of the electromagnet against the force of the recall spring 118 and rotates the anchor A₁ about its pivot a to bring said anchor in the position shown in Fig. 9. In this position, the arm 115 engages the pinion 104 which is thus stopped. The pinion 108 which is keyed to the shaft 62' rotates bodily with the latter and causes the planet wheel 106 to roll on the pinion 104 through the planet wheel 105, thereby rotating the planet wheel carrier gear 107 which in turn transmits movement to the platen roller 5 through the gear 109 and the ratchet 111. Now the platen roller is driven by the motor M for driving the paper feeding device E_p. It is to be noted that, in this case, the arm 114 of the anchor A₁ closes a contact 119 which controls letting in of the platen roller clutch.

25 When the electromagnet 117 is not energized, its armature 116 is recalled in the position shown in Fig. 8 by the spring 118. The anchor A₁ moves into position shown in Fig. 8 where the arm 115 is disengaged from the pinion 104, the arm 114 engaging the planet wheel carrier gear 107 thereby stopping the latter. Under this condition the pinion 104 is driven by the shaft 62' and by the motor M through the planet wheels 105 and 106 which rotate about their respective pins (which are at this moment fixed in the space) under control of pinion 108. From the pinion 104 the move-

ment is transmitted to the upper roller 24 by the system of gears 103, 102, 35.

Thus it will be seen that the account sheet or the statement sheet may be fed by a variable pitch by selectively driving the upper roller 24 or the platen roller 5 through the paper feeding mechanism Ep. Feeding is effected in the interval between letting in of the paper feeding mechanism clutch upon energizing of the electromagnet Em and declutching of the same mechanism, generally by movement of one of the perforations of the record sheet which is fed under a suitable analyser brush, in a manner to be described hereinafter. It is to be noted however that the roller 24 and the platen roller 5 are selectively driven and may not be operated simultaneously. A special electric control device prevents the lower roller 5 from rotating before the upper roller 24 rotates, for feeding the account sheet previously to the statement sheet.

Intermediate carbon paper feeding device.—Referring again to Figs. 1 and 7, the roller 120 which carries the intermediate carbon paper c is adapted to be driven from the shaft of the platen roller 5 through a pair of grooved pulleys 121 and 121' rigid with the same shaft and of different diameters to provide a suitable speed reduction. Roller 120 is connected to roller 5 through spring belts 122 cooperating with a grooved pulley 123 rigid with roller 5, pulleys 121 and 121', and a grooved pulley 124 rigid with roller 120. Roller 125 is connected to roller 120 by means of a spring belt.

It will be seen that both carbon paper rollers 120 and 125 are adapted to rotate at a much lower speed than roller 5. Thus the carbon paper is slowed down and is fed with a very small pitch upon feeding of the account sheet or of the statement sheet, thereby providing a plurality of printings in substantially the same location of the carbon paper, said printings being nevertheless of a good quality. Thus a feed of $\frac{1}{2}$ in. of the account sheet may correspond to a feed of $\frac{1}{4}$ in. of the intermediate carbon paper c, thereby providing much saving of carbon paper. Said slowing down of the carbon paper is provided by the fact that feeding thereof is not controlled by the friction rollers 7; the carbon papers pass freely around the platen roller 5 and are fed by adherence, regardless of the feeding of the account sheet or of the statement sheet, which forms an essential feature of the novel carbon paper feeding mechanism.

General wiring diagram.—There will be now described the electric circuits of the device of the invention, as well as the connections thereof to the alphabetic and numeric printing tabulating machine having mounted thereon said device. In order that the following part of this specification may be clearly understood, there will be described, as it proceeds, the operation of the machine, which operation will consist, for instance, in: simultaneous printing, on the one hand, of the accounts of the coupons cut from the deeds deposited in the cashes of a bank for each customer, and on the other hand, of the statements of said accounts for each office of said bank. Thus, by means of the improved device of the invention, there may be simultaneously and rapidly sent to different offices the statements corresponding to each office and recapitulating the accounts pertaining to each customer.

For this purpose the account sheet or the statement sheet must be sometimes fed automatically by a variable pitch. Thus when the account to

be printed corresponds to another customer than the customer pertaining to the next account, there will be a changement of card in the customer number, i. e., in the number perforated in the cards to designate a given customer. Said changement of the customer number indicating perforations is detected by the upper control brushes UB of the tabulating machine which co-operate in the usual manner with the lower adding brushes LB. The automatic minor control of the tabulating machine becomes operative; however there are to be considered two different cases:

1. The customer number changement occurs before the account, which is in printing position, is terminated.

In this case the account sheet must be fed by a variable pitch to bring a predetermined line, which is intended to comprise the amount of the coupons, in printing position; the total representing said amount must be printed, and then the account sheet must be fed to bring the first line of the next account in printing position to continue printing of the item lines pertaining to the coupons of another customer. The statement sheet must be fed meanwhile line by line after each printing, regardless of the feed pitch of the account. When the number of lines to be printed for each office exceeds the length of the statement sheet, the latter must be automatically fed, after printing of the last line thereof, to bring the first line of the statement sheet which follows in printing position.

Upon a changement of the office number, the major control of the tabulator becomes operative and a major total is printed; after said printing, the statement sheet must be fed to bring the first line of the next statement sheet in printing position, and as there will be necessarily a change-

ment of customer number simultaneously with the office changement, the account sheet must be fed too, as described hereinbefore. Furthermore, in order to avoid printing of an office total on an account intended to be sent to the customer, the account sheet must be fed as to overlook the next account on which will be printed the office total, which account will be detached afterwards. The loss of one form may be avoided by employing a statement sheet wider than the account sheet and by printing the office total on the portion of the statement sheet which exceeds the account sheet.

2. The changement of the customer number does not occur before the account is terminated.

In this case, the account sheet must be automatically fed, after printing of the last line thereof, to bring the first line of the next account in printing position; however the account must not be brought in printing position in the location of printing of the customer minor total as in the preceding case. Feeding of the statement sheet must be effected in the aforescribed manner.

Referring now to Figs. 16 to 19 inclusive, the plug connections are shown in full strong lines.

3. There will be now described in a more detailed manner the operation of our novel device adapted to feed the record sheet in the aforesaid manner. It will be observed that in the preferred form of embodiment the intermediate tabulator control becomes operative upon a changement of the customer number, by means of a plug connection 129 shunting on the line the minor control relay 126 of said tabulator and the intermediate control relay 127 thereof.

Referring more particularly to Fig. 16, ener-

gizing of relay 126 is effected upon a minor control changement through a circuit comprising line wire L-1, terminal L-5, cam switch CB-16, cam switch CB-17, contacts Rn-B, plug connection 130, terminal 131, relay 128, conductor bar 132, fuse F-18 and line wire L-2. Relay 127 is energized by a circuit derived from socket 131 and comprising plug connection 129, relay 127, bar 132, fuse F-18 and line wire L-2.

Energizing of relays 126 and 127 causes closing of the associated contacts R-126-B and R-127-B respectively. Closing of contact R-126-B causes energizing of the minor relay 28-M₁ by completion of a circuit comprising line wire L-1, terminal L-5, contact R₃BC (which is closed in this moment by the usual card lever relay energized when a card appears at the lower brush station), bar 133, cam switch CF-1 of the card feeding mechanism (the contacts of said switch being closed in this moment), wire 134, contact R-126-B, switch 135, relay 28-M₁, bar 136, wire 137, cam switch CB-19, fuse F-18 and line wire L-2.

Energizing of the minor relay 28-M₁ effects in the tabulating machine the control operations by closing of the three-blade switches M₁-11 and M₁-12 adapted to control in the device of the invention feeding or stopping of the account sheet, as will be described hereinafter.

The device of the invention is connected to the intermediate control socket 151 of the tabulating machine, and said socket is connected to wire 134 through contact R-127-B adapted to close with contact R-126-B, but it is not connected as usual to the intermediate control relay 27-Int of the tabulating machine by reason of opening of switch 138 which is in the position shown in full lines in Fig. 16, in order to avoid completion of accidental back circuits in the tabulating machine.

On the other hand, the major control of the tabulator becomes operative upon a changement of office number, and the major control relay 128 is energized through plug connection 139 which connects contacts R-n-B to relay 128. Said energizing causes the associated contact R-128-B to be closed, thereby completing a circuit which comprises line wire L-1, terminal L-5, switch R₃BC, wire 135, cam switch CF-1, wire 134, contact R-128-B, switch 140, major relay 28-M₂, bar 136, wire 137, cam switch CB-19, fuse F-18 and line wire L-2.

Energizing of the major relay 28-M₂ causes closing of its associated contact R-28-B, thereby energizing the intermediate relay 27-Int, which in turn causes its associated contact R-27-C to be closed, thereby energizing the minor relay 28-M₁.

Energizing of the relay 27-Int causes its associated contact R-27-A to be closed, thereby energizing the relay 312 by completion of a circuit comprising line wire L-1, terminal L-10, wire 141, cam switch PM-8, bar 142, contact R-27-A, wire 143, relay 312, bar 144, fuse F-18 and line wire L-2. It is the relay 312 which controls, in a manner to be described hereinafter, the feed control of the account sheet upon an office changement by opening of its associated contacts 312-A and 312-B and by movement of the central blade of its three-blade contact 312-C into a position opposed to the position shown in Fig. 19.

Having shown the operating conditions of the minor and major controls of the tabulating machine having mounted thereon the device of the

invention, there will be now described the operation of said device during movement of the record sheets and associated to a changement between a pair of consecutive forms of either a customer number changement or an office number changement.

Changement of a customer number.—The movement of the record sheets 1 and 2 are illustrated in diagrammatic manner in Figs. 24 to 28 inclusive. Arrow f shows the direction of feeding of said sheets with regard to the printing position represented by the type line T of the tabulator printing mechanism. The sheets 1 and 2 are of the same width, and comprise in each edge thereof a series of perforations c₁, c₁' and c₂, c₂' adapted to cooperate respectively with brushes b₁, b₁' and b₂, b₂' and with contact plates p₁ and p₂.

Fig. 24 shows the relative positions of the account sheet 1 and of the statement sheet 2 at the end of the first feed s₁¹ of the sheet 1 when a changement of customer number occurs. Referring to Fig. 25, which shows the next feed s₂¹ of sheet 1, the following account pertains indeed to Jean, while the account which is in printing position in Fig. 24 pertains to Pierre. Therefore the customer number has changed from one account to the next one, viz. it has changed from 640 to 641, in this example. The office number 35 however has remained unchanged.

In this condition, the only control of the tabulator which becomes operative is the minor control which causes, in a manner hereinbefore described, closing of contacts M₁-11, M₁-12 and R-127-B. The clutch electromagnet Em has its energizing circuit completed through the device of the invention, said circuit comprising line wire L-1, terminal L-5, contact R₃BC (which is closed in this moment), wire 134, contact CF-1 (closed in this moment), wire 134, contact R-127-B, socket 151, plug connection 145, double socket 146, contact D₂ normally closed, double winding relay 304, and furthermore across the terminals of said relay, relay 313 and clutch electromagnet Em with contact 303-B, contact D₁ normally closed, cam switch CB-35 closed in this moment, wire 147, lower terminal of relay 305, wire 148, contact 301-A (which opens only when paper end brush 200 engages plate p₁, thereby causing energization of relay 301), lower terminal of relay 301, wire 149, switch 150, wire 152, fuse F-24 and line wire L-2.

It will be observed that energization of clutch electromagnet Em is controlled by closing of cam switch CB-35 which thus causes paper feed starting. Said electromagnet Em causes, when energized, attraction of its armature 62, thereby moving lever 64 and operatively engaging the clutch elements 56, 56' to transmit rotation from motor M to the upper feed roller 24 through gears 183-182-35, the electromagnet 117 of the differential device D₁ being not energized. The account sheet fed by said roller 24 moves to a pitch s₁¹ which terminates, as shown in Fig. 24, as the account line which shall have printed thereon the partial total representing the amount 105.65 of the coupons of Pierre is in printing position T registering with the types of the printing mechanism of the tabulating machine.

Stopping of the account sheet in this very moment is ensured by suitably setting of the brush 201 which now engages the plate p₁ through the perforation c₁ of the second account following the account which is in printing position. Said brush completes a circuit comprising line wire

L-1, terminal L-16, wire 153, terminal 154, wire 155, contact D₃ normally closed, wire 156, contact plate p₁, perforation c₁, brush 201, double socket 157, plug connection 158, socket 159, three-blade contact M_i-12 (the central blade thereof being in a position opposed to that shown in Fig. 18, thereby ensuring closing of the contact under the minor control), wire 160, socket 161, plug connection 162, socket 163, wire 164, terminal 165, contact E_m-166 of clutch lever (which contact is closed by attraction of the armature of electromagnet E_m), terminal 166, contact A₂ (normally open, but closed in this moment by reason of energization of relay A which is controlled, as will be seen hereinafter, by brush 202 having engaged, a small distance in advance of the end of the account, a perforation c₁ for slowing down the speed of motor M at the end of feed), wire 167, bar 168, relay 302 and 303 (shunt mounted), wire 169, fuse F-24 and line wire L-2.

Relay 303 upon being energized closes its associated contact 303-A, thereby completing a stick circuit for relays 302 and 303, said circuit comprising line wire L-1, terminal L-16, wire 153, plug 154, wire 175, contact 304-AS (closed by energization of relay 304), contact 303-A, wire 168, relay 303, wire 169, fuse F-24 and line wire L-2.

The double winding relay 304 is itself maintained energized by completion of a stick circuit comprising line wire L-1, terminal L-16, wire 153, terminal 154, wire 170, contact D_b-170 of clutch disengaging electromagnet D_b (said contact being open when D_b is energized), contact 304-BS (closed in this moment), stick circuit 304m of relay 304, resistor 171, wire 172, lower terminal of relay 301, wire 148, switch 150, wire 152, fuse F-24 and line wire L-2.

Relays 302 and 303 upon being energized close their contacts 303-C, 302-A, 302-B and 302-C mounted in the circuit of the clutch disengaging electromagnet D_b, thereby energizing said electromagnet D_b by completion of a circuit which comprises line wire L-1, terminal L-16, wire 153, terminal 154, wire 176, electromagnet D_b, wire 177, contact 303-C, 302-A, 302-B, 302-C (closed in this moment), wire 178, fuse F-24 and line wire L-2.

Said clutch disengaging electromagnet D_b may also be manually energized by actuating a de-clutching push-button associated with contact 179 to shunt the four contacts 303-C, 302-A, 302-B, and 302-C.

Energizing of D_b causes attraction of armatures 65, Fig. 14, and thereby movement of lever 64 in a direction opposed to that controlled by the electromagnet E_m. Therefore the elements 56, 56' are declutched, the shaft 62 is disengaged from the motor M and the differential device D₁ is stopped. Thus the upper roller 24 is stopped and the account sheet remains in the position shown in Fig. 24.

The armature 65 sticks for a short time to the poles of the electromagnet D_b, and contact D_b-170 opens meanwhile, thereby interrupting the stick circuit of the double winding relay 304. As soon as relay 304 is no more energized, contact 304-AS opens, thereby deenergizing relays 302 and 303. Therefore the contacts 303-C, 302-A, 302-B and 302-C open and interrupt the circuit of the electromagnet D_b, thereby providing the recall of the armature 65 in its rest position.

After resetting of the declutching means the tabulating machine prints in the usual manner

the customer's minor total (105.65 in this instance), which total is simultaneously printed on the account and on the statement which has been fed by one line space after feeding of the account. After printing of the minor total, the central blade of contact M_i-12 comes back to the position shown in Fig. 18.

The account sheet is now ready for a new feed under the control of the paper feeding mechanism E_p. This second feed s₂ has for its purpose to bring the first line of the next account into printing position. The new positions of the sheets 1 and 2 with regard to the printing position T are shown in Fig. 25.

15 The following circuits are completed: First, a circuit comprising line wire L-1, terminal L-16, wire 153, terminal 154, wire 180, contact M_i-11 (the central blade of which is in a position opposed to that shown in Fig. 19 by reason of the minor control being operative as hereinbefore disclosed), wire 181, contact 312-C comprising three blades, which contact is normally closed, wire 182, double socket 183, plug connection 184, socket 185, wire 186, cam switch PM-17 (adjusted to be closed after printing of a total), wire 187, relay 309, wire 188, cam switch CF-36, fuse F-20 and line wire L-2. Completion of said circuit causes the relay 309 to be energized, thereby closing its associated contacts 309-A and 309-C thus to prepare an energizing circuit for the clutch electromagnet E_m, especially by closing contact 309-A. Said circuit comprises: line wire L-1, terminal L-16, wire 153, terminal 154, wire 189, contact 309-A (closed by reason of relay 309 being energized), wire 190, socket 191, plug connection 192, double socket 146, contact D₂ (normally closed), relay 304 (with double winding), and furthermore (across the terminals of said relay) relay 313 and clutch electromagnet E_m with contact 303-B; contact D₁ (normally closed), cam switch CB-35 (closed in this moment), wire 147, lower terminal of relay 305, wire 148, contact 301-A, lower terminal of relay 301, wire 149, switch 150, wire 152, fuse F-24 and line wire L-2.

By reason of electromagnet E_m being energized, the upper feed roller 24 restarts for rotation and the account sheet is fed into the position shown in Fig. 25 where it is stopped upon engagement of the declutching brush 203 with the contact plate p₁ through the perforation c₁.

Spacing between the brushes 201 and 203 has been selected to be of the same length as feed s₂ as is shown in Fig. 25.

55 The circuit which is completed by engagement of the brush 203 through the perforation c₁ comprises line wire L-1, terminal L-16, wire 153, terminal 154, wire 155, contact D₃ (normally closed), wire 156, plate p₁, brush 203, socket 193, plug connection 194, socket 195, contact 312-A (normally closed and not being opened by reason of absence of any change of office number for operating the major control), three-blade contact M_i-12 (the central blade of which has come back into the position shown in Fig. 18 after printing of the minor total), wire 160, socket 161, plug connection 162, socket 163, wire 164, terminal 165, contact E_m-166, terminal 166, contact A₂, wire 167, bar 168, relays 303 and 302 (shunt mounted), wire 169, fuse F-24 and line wire L-2.

65 Energizing of relays 302, 303 causes, as shown hereinbefore, energizing of the declutching electromagnet D_b to stop the account sheet as the first line of the account pertaining to Jean comes

into the printing position T. The statement sheet has meanwhile moved by one line space, and is located as shown in Fig. 25.

From this moment both sheets 1 and 2 are fed by one line space after printing of each item line; however there may be a case where the number of item lines to be printed on an account sheet is too great for being printed on one account, which is the case of the Jean account. It is now necessary to carry out a number of operations which will be described hereinafter.

At first, the account sheet must be fed from the last line of the Jean account, which comprises the item 14.55 visible in Fig. 26, to the first line of the next account for printing thereon the item 32.20 in this instance (Fig. 27).

In other words, the line to be brought into the printing position T is the first line of the next account and not, as in the preceding example, the line of the account on which shall be printed the total representing the amount of the coupons of the account. The length of feed s_1^1 is shown in Fig. 27.

Feeding is started upon engagement of a brush 204 adapted to detect the end of an account with a perforation c_1' arranged opposite the perforation c_1 ; in this moment, the account sheet 1 is in the position shown in Fig. 26. A circuit is completed which comprises line wire L—1, terminal L—16, wire 153, terminal 154, wire 196, contact plate p_1 , perforation c_1' , brush 204, socket 197, plug connection 198, double socket 146, contact D_2 (normally closed), relay 304 (comprising a double winding) and electromagnet Em (connected across the terminals of 304), contact D_1 (normally closed), contact cam CD—35 (closed in this moment), wire 147, lower terminal of relay 305, wire 148, contact 301—A, lower terminal of relay 301, wire 149, switch 150, wire 152, fuse F—24 and line wire L—2. Energizing of the clutch electromagnet Em causes, as in the preceding case, rotation of the upper roller 24 and feeding of the account sheet 1.

During the feed s_1^1 perforation c_1 passes under the brush 201; however, as there is no change in the customer number which is still 641, the central blade of contact M_1 —12 remains in the position shown in Fig. 18, and therefore the energizing circuit of relays 302 and 303, as well as of the declutching electromagnet D_b is not completed. Sheet 1 is not stopped and continues its movement until perforation c_1 passes under the brush 203, thereby energizing the relays 302 and 303 to stop the account sheet, as described hereinbefore.

It will be noted that before passing under the brush 203, the perforation c_1 had passed under a starting brush 205 the function of which will be described hereinafter.

On the other hand, when the statement, which comprises the recapitulation of the Jean and Pierre accounts, comes to end, it must be fed from its last line to the first line of the next statement, i. e., by feeding it to be stopped as the first line of the next statement comes into printing position, said position being illustrated by line T. The length of feed s_1^2 is shown in Fig. 26.

Feeding of the statement sheet is of course preceded by feeding of the account sheet, which is initiated either by a change of customer number or upon terminating of an account sheet when the number of lines to be printed thereon exceeds the available height of said account sheet.

Starting of the statement sheet is initiated as soon as perforation c_1' passes under brush 206,

thereby detecting the end of said statement sheet, as is shown in Fig. 28, by completion of a circuit comprising line wire L—1, terminal L—16, wire 153, terminal 154, wire 196, contact plate p_2 , perforations c_1' , brush 206, plug 211, double socket 212, plug connection 213, socket 214, relay C, wire 215, conductor bar 216, wire 217, fuse F—24, line wire L—2. Another circuit is simultaneously completed which comprises the portion of the preceding circuit from line wire L—1 to double socket 212 inclusive, and therefrom: plug connection 218, socket 219, relay E, conductor bar 220, and back circuit as above through wire 217 to fuse F—24 and line wire L—2.

15 The stick circuits of the relays C and E are the following:

Stick circuit of relay C comprises line wire L—1, terminal L—16, wire 153, terminal 154, wire 155, contact D_2 (normally closed), contact C_2 of relay C, bar 221, stick coil C' of relay C, wire 222, bar 220, and back circuit through wire 217 to fuse F—24 and line wire L—2.

Stick circuit of relay E comprises line wire L—1, terminal L—14, wire 223, plug 224, wire 225, 25 upper terminal 226 of relay R₄ of the clutch electromagnet C_{imp} of the card feeding mechanism of the tabulating machine, wire 227, contact 305—A (normally closed), wire 228, contact E—2 of relay E, bar 229, stick coil E' of relay E, bar 220, 30 wire 217, fuse F—24 and line wire L—2.

Said stick circuits are adapted to be opened in the following manner: Stick circuit of relay C is opened upon energizing of the double winding relay D—D' which opens its contact D—6, and 35 stick circuit of relay E is opened upon energizing of relay 305 provided for automatic card feeding starting, which relay opens the contact 305—A. The function of said relay 305 will be disclosed hereinafter.

40 When relays C and E are thus energized by the passage of the perforation c_1' under the brush 206, they cause closing of a plurality of contacts, viz. contact E_1 adapted to open the energizing circuit of the clutch electromagnet C_1 of the card feed-

45 ing mechanism (which circuit comprises line wire L—1, terminal L—17, tabulator contacts, contact E_1 , electromagnet C_1 , contact 305—C, cam switch CB—36, switch 246, switch 150, wire 152, fuse F—24 and line wire L—2), and contacts

50 E_2 , C_3 adapted to complete the energizing circuit of relay D—D'. The latter circuit comprises line wire L—1, terminal L—16, wire 153, terminal 154, wire 170, contact D_b —170, wire 230, left-hand blade of contact A in Fig. 18, bar 231, wire 232, contact CB—A, contact E_3 , contact C_3 , contact

55 27—AL, contact 26—AL, contact 304—AI (all contacts from CB—A to 304—AI inclusive are normally closed and adapted to be opened by the minor, intermediate or major control), relay 60 D—D', wire 211, fuse F—24 and line wire L—2. When relay D—D' is energized, it completes its stick circuit by closing of contact D_4 which shunts the series of contacts 304—AI, 26—AI, 27—AL, C_3 , E_3 and CB—A; simultaneously relay D—D'

65 upon being energized moves the median blade of the three-blade contact D—7 in a position opposite to that shown in Fig. 17, thereby to cause energizing of the clutch electromagnet 117 of the platen roller.

70 The energizing circuit of the electromagnet 117 comprises line wire L—1, terminal L—16, wire 153, terminal 154, wire 233, electromagnet 117, contact D—1, bar 216, wire 217, fuse F—24 and line wire L—2.

75 It will be remembered that it is the electro-

magnet 117 which upon being energized causes the anchor A₁ of the differential device D₁ to rotate about its axis a into the position shown in Fig. 9 where the platen roller 5 is adapted to be driven from the motor M of the paper feeding mechanism E_p.

Furthermore, there must be initiated feeding of the statement sheet by energizing of the clutch electromagnet E_m. For this purpose, energizing of the relay D—D' causes the median blade of contact D—3 to move into a position opposite to that shown in Fig. 17, thereby eliminating the contact plate p₁ and inserting the contact plate p₂.

On the other hand, energizing of relay D—D' causes the median blades of the contacts D—1 and D—2 to move in a position opposite to that shown in Fig. 18, thereby opening the circuits which have caused energizing of the clutch electromagnet E_m for previous feeding of the account sheet and completing an energizing circuit of the electromagnet E_m, which circuit comprises line wire L—1, terminal L—16, wire 153, terminal 154, wire 155, median blade of contact D—3, wire 234, lower blade of contact D—2, relay 304, 313 and electromagnet E_m, contact 303—B, contact D—1, contact 119 for platen roller clutch (formed by the arm 114 of the anchor A₁ upon energizing of said electromagnet 117), contact CB—B, wire 235, lower blade of contact CB—35, wire 147, lower terminal of relay 305, wire 148, contact 301—A, lower terminal of relay 301, wire 149, switch 150, wire 152, fuse F—24 and line wire L—2.

The clutch electromagnet E_m which is thus energized causes now the platen roller to rotate, the differential device D₁ switching the drive on said roller by reason of electromagnet 117 being previously energized.

Feeding of the statement sheet continues until brush 207, which is spaced from brush 206 by the length of s₁², engages the contact plate p₂ through the perforation c₂ of said statement sheet, thus permitting energizing of relays 302 and 303, and therefore energizing of the electromagnet D_b by completion of a circuit which comprises line wire L—1, terminal L—16, wire 153, terminal 154, wire 155, contact D—3 the median blade of which is in a position opposite to that shown in Fig. 17, wire 236, plate p₂, perforation c₂, brush 207, terminal 237, double socket 238, plug connection 239, socket 163, wire 164, contact E_m—166, terminal 166, contact A—2, wire 167, bar 168, relays 302 and 303, wire 169, fuse F—24 and line wire L—2.

Declutching of the mechanism E_p causes the statement sheet to be stopped in the position shown in Fig. 26.

Finally, the relays C and E are deenergized by opening of contact D—6 upon energizing of relay D—D' and opening of contact 305—A controlled by energizing of the automatic card feed starting relay 305.

The device of the invention is now ready to restart operation as above.

There will be now described the operation of said relay 305 which is energized shortly before the statement sheet or account sheet is stopped, and which cooperates with brushes 208 and 205 arranged somewhat behind the statement declutching brush 207 and the account declutching brush 203.

Automatic card feed starting relays and Brushes.—The paper feeding mechanism E_p is adapted to feed the account sheet 1 or the statement sheet 2 to a given pitch during one oper-

ative cycle, corresponding to one card passage through the tabulating machine, and any increase of said pitch will be detrimental for the paper positioning; in other words, as the paper feeding pitch increases during one card passage cycle, there is a risk of impairing the exact positioning of the paper by reason of the paper feeding speed being increased.

Hence, there may be a case where the statement or the account must be fed to a pitch much greater than the above-mentioned pitch. In said case, in order to avoid any deviation of paper positioning from printing line T, due to the great speed selected for the motor M, card feeding of the tabulating machine is stopped by opening of contact E₁ upon energization of relay E to permit feeding of the paper, and the purpose of relay 305 consists in controlling restarting of said feed shortly before record sheet feeding is terminated.

There will now be described said restarting means, and it will be noted previously that for this particular operation the automatic starting switch Int—11 ordinarily provided in alphabetic and numeric printing tabulators is in open position.

Starting of the statement, previous to the end of feeding, is initiated by a contact controlled by a brush 208 cooperating with the contact plate p₂ through the perforation c₂ of said statement, shortly before said perforation c₂ passes under the brush 207. The relay 305 has an energizing circuit thereof completed which comprises line wire L—1, terminal L—16, wire 153, terminal 154, wire 199, plate p₂, perforation c₂, brush 208, socket 240, wire 241, socket 242, plug connection 243, socket 244, wire 245, relay 305, wire 148, contact 301—A, lower terminal of relay 301, wire 149, switch 150, wire 152, fuse F—24 and line wire L—2.

Relay 305 upon being energized closes its contact 305—C, Fig. 17, thereby completing an energizing circuit of the clutch electromagnet C_a of the card feeding mechanism.

It will be noted that said circuit (which comprises line wire L—1, terminal L—17, tabulator contacts, contact E—1, electromagnet C_a, contact 305—C, cam switch CB—36, switch 246, switch 150, wire 152, fuse F—24 and line wire L—2) may be completed by reason of contact E—1 being closed, relay E being de-energized by reason of contact 305—A being opened. Relay 301 is maintained energized by completion of a circuit comprising line wire L—1, terminal L—11, bar 270, cam switch CF—22, cam switch CF—34, contact 305—B (closed by energizing of 305), relay 305, wire 148, contact 301—A, lower terminal of relay 301, wire 149, switch 150, wire 152, fuse F—24 and line wire L—2.

In this condition the next card is fed under the analyzer brushes of the tabulating machine.

When the paper is fed, for instance, during the passage of a pair of cards under the tabulator brushes, the card feeding mechanism would cease operating during a pair of cycles and restart only later on when the starting brush contacts its associated plate through the perforation c₂.

Relay 305 may also be energized by brush 205 which operates in a similar manner in view of restarting of the account sheet, shortly before a long feed is terminated.

The energizing circuit of relay 305 comprises in this case line wire L—1, terminal L—16, wire 153, terminal 154, wire 198, plate p₁, perforation c₁, brush 205, socket 247, wire 248, contacts 310—BS,

311—BS, contact 312—B, contact C₁, relay 305, wire 148, contact 301—A, lower terminal of relay 301, wire 149, switch 150, wire 162, fuse F—24 and line wire L—2.

The above circuit is adapted to be opened by opening of the contacts 310—BS, 311—BS, or contacts 312—B, C₁ which are adapted to eliminate operation of said brush 205 in certain cases, particularly when sheet 1 must be fed by the length of one form in order to avoid printing of a statement total on an account intended to be sent to a customer, both sheets 1 and 2 being of course assumed to be of the same width. In this case, said brush 205 must not cause restarting of card feeding of the tabulating machine upon engagement thereof through said account perforation c₁, for during feeding of said account sheet there are yet items to be printed on the statement sheet, and the card feeding mechanism must remain motionless. It is the relay 312 which upon being energized as the tabulator major control becomes operative, opens its contact 312—B, thereby interrupting the energizing circuit of said relay 305.

Changement of office number.—Referring now to Figs. 29 to 31 inclusive, there will be described the different operations relating to a changement of office number. Said operations may provide the changement of office number in any location of the statement sheet. In this instance, said changement occurs in the eighth line of the statement sheet. Said line, which comprises the item 11.45, pertains to account No. 642 of Jacques and to office No. 35. The office number passes from 35 to 37, as shown in Fig. 31, and simultaneously therewith there is a change of customer: No. 642 to Jacques becomes No. 643 to André.

The first step of operation is feeding of the account sheet by a pitch s₁¹ in order to bring in printing position the line of the Jacques account on which must be printed the minor total 81.15. Said feed shown in Figs. 29 to 31 inclusive is initiated, as the preceding feed s₁¹ shown in Fig. 24, upon energizing of the clutch electromagnet E_m, particularly through the plug connection 145; the end of said feed s₁¹ is provided as in the preceding case upon engagement of the declutching brush 201 with the plate p₁ through the perforation c₁ of the second account following the Jacques account.

After this first step of the account sheet, the statement sheet is fed by one line space and the minor total is simultaneously printed on the statement and on the account which are in the positions shown in Fig. 29, said minor total being 81.15.

After printing of the minor total, the device of the invention provides again feeding of the account sheet to bring the location of the major total into printing position.

Said second step s₁¹ is initiated as above by energizing of the clutch electromagnet E_m due to closing of contact 309—A controlled by relay 309 which is operated by completion of a circuit comprising line wire L—1, terminal L—16, wire 153, terminal 154, wire 180, three-blade contact Mi—11 (the central blade of which is in a position opposite to that shown in Fig. 19 by reason of operation of the minor control), wire 249 (by reason of the central blade of said three-blade contact 312—C being in a position opposite to that shown in Fig. 19 upon operation of the major control due to change of office number), socket 250, plug connection 251, double socket 183, plug connection 184, socket 185, wire 186, cam switch

PM—17, wire 187, relay 309, wire 188, cam switch CF—36, fuse F—20 and line wire L—2.

On the other hand, as the major control becoming operative energizes the relay 312, thereby causing its associated contacts 312—A and 312—B to be opened, the declutching brush 203 and the automatic starting brush 205 do not become operative as the perforation c₁ of the next account sheet passes thereunder during said feed s₁¹.

10 The account sheet is stopped at the end of feed s₁¹ in the usual manner by energizing of the declutching electromagnet D_b as the brush 201 engages the plate p₁ through the perforation c₁ of the next form. The record sheets are now in the position shown in Figure 30.

After said second step of the account sheet, which is followed by feeding of the statement sheet to one line space, the major office total is printed thereon, said total being in this instance 20 459.45.

25 The device of the invention now provides a third feed of the account sheet, the pitch of which is the same s₂¹ as in Fig. 25, to bring the first line of the next account, which pertains to André, into printing position. Starting of the account sheet is initiated upon energizing of the clutch electromagnet E_m by completion of a circuit described above and prepared by closing of contact 309—A upon energizing of relay 309. The latter 30 relay is now energized by said central blade of three-blade contact Mi—11 returning into the position shown in Fig. 19, said return occurring between printing of the minor total and printing of the major total. In this case the energizing 35 circuit of relay 309 comprises line wire L—1, terminal L—16, wire 153, terminal 154, wire 180, contact Mi—11 (the central blade of which is in the position shown in Fig. 19), wire 252, cam switch PM—18, contact 312—C (the central blade of which is in the position opposite to that shown in Fig. 19 by reason of operation of the major control and of energizing of relay 312), wire 182, double socket 183, plug connection 184, socket 40 185, wire 186, cam switch PM—11, wire 187, relay 309, wire 188, cam switch CF—36, fuse F—20 and line wire L—2.

45 The account sheet is stopped in the usual manner as the perforation c₁ of the following form 50 passes under the declutching brush 203, as shown in Fig. 31. The energizing circuit of the electromagnet D_b has been disclosed hereinbefore and will not be described now.

55 In the following will be described the operation of the device or the invention with reference to feeding of the statement sheet.

Energizing of relays C and E is not initiated by means of the brush 206, the perforation c₂ cooperating with said brush not yet being engaged under the latter by reason of the statement sheet not being terminated. Said relays C and E are however energized through plug connection 253 which connects the double socket 212 to the double socket 254 of the tabulating machine. The double socket 254 is connected to line wire L—1 by a circuit comprising terminal L—3, wire 255, contact R—22—BI, contact Mi—8 (the central blade of which is in the position shown in Fig. 16 by reason of operation of the minor control), upper blade of contact Ma—5 (the central blade of which is in the position shown in Fig. 16 when the major control becomes operative), contact Int—6 (closed by energizing of the control 60 70 relay of intermediate control which becomes

operative, as shown with reference to minor and major controls), and double socket 254.

The other part of the energizing circuits of C and E comprised between the double socket 212 and the line wire L-2 has been disclosed hereinbefore, and will not be described therefore.

Besides it will be noted that the consecutive energization of relay D-D', Fig. 17, is delayed and will not occur during printing of the minor and major totals, the contacts 27-AL and 26-AI being open. In this condition, during the time of printing minor and major totals, the clutch electromagnet 117 of the lower platen roller does not drive said roller, and the paper feeding mechanism E_b is still connected through the differential device D_b to the upper roller 24.

Said contacts 26-AI and 27-AL are closed only after printing of the major total, viz. 459.45, Fig. 31.

As on the other hand the contacts C-3 and E-3 are previously closed by reason of energizing of relays C and E, the double winding relay D-D' is energized as the contact CB-A is closed, thereby closing contact D-7 and therefore energizing the clutch electromagnet 117 of the platen roller 5. The shaft 62 of the paper feeding mechanism is then adapted to be driven by the motor M and to drive the platen roller by suitable positioning of the anchor A_b. The platen roller 5 starts rotating and feeds the statement sheet as the clutch electromagnet E_b is energized upon movement of the central blades of the three-blade contacts D-1 and D-2 in the opposite position to that shown in Fig. 18, under the control of relay D-D'.

Now the statement sheet is fed by a pitch s_2^2 from the printing line of the major total 459.45 to the first line of the next statement, which line comprises the item "37-643-André-8.25" and comes into printing position.

Feeding is terminated as the perforation c₂ of the next statement passes under the declutching brush 207 the spacing of which from the brush 206 has been selected to correspond to the pitch s_2^2 . The energizing circuit of the declutching electromagnet D_b is the same as that which has been described hereinbefore. Now the statement sheet is in the position shown in Fig. 31.

The device of the invention permits carrying out of a plurality of other operations as there are different connections to be effected on the switchboard associated to said device.

Printing of progressive totals.—There will be now described a very advantageous operation which calls for a modification of setting of the brush spacing, as well as for provision of new connections which are shown, as the preceding connections which are maintained, in full and strong lines in Figs. 20 to 23 inclusive. In the following there will be always assumed that the record sheets are of the same width, thus causing the loss of one form, when it is desired, as will be seen hereinafter, to avoid printing of a progressive total on an account intended to be sent to a customer.

Figs. 32 to 35 inclusive show in a diagrammatic manner the different positions of the record sheets relatively to the printing position T during the operations which will be described hereinafter and which comprise more particularly: printing of a progressive total at the end of a statement, where a paper feed brings the first line of the statement which follows into printing position, and a new printing of the progressive

total, both printings of progressive total being effected on a blank account sheet which will be detached from the sheet 1 after the operation.

As the last line of the statement is printed, i. e. when the lines comprising each the item 31.10 of the sheets 1 and 2 are in printing position (Fig. 32), the brush 206 engages the plate p₂ through the perforation c₂ thereby causing the relays C and E, Fig. 21, to be energized by the above-mentioned circuits which are maintained by completion of their respective stick circuits, as shown hereinbefore. The contacts associated to said relays C and E are opened or closed according to the requirements of each case, as will be seen hereinafter. More particularly, contact E₁ which is inserted in the energizing circuit of the clutch electromagnet C₁ of the card feeding mechanism of the tabulator is opened, thereby stopping the feed of cards through said machine. On the other hand, closing of contacts E-4 and C-4 energizes relays 307 and 308, thereby completing a progressive total circuit comprising line wire L-1, terminal L-16, wire 153, terminal 154, wire 256, contact E-4 (closed in this moment), contact F-1 (normally closed), contact C-4, wire 257, socket 258, plug connection 259, socket 260, wire 261, contact 304-BI (controlled by double winding relay 304), wire 262, relay 307, bar 263, contact 310-A, wire 264, lower blade of contact CB-35, wire 147, lower terminal of relay 305, wire 148, contact 301-A, lower terminal of relay 301, wire 149, switch 150, wire 152, fuse F-24 and line wire L-2. Relay 308, Fig. 22, which shunts the relay 307 is also energized by the above circuit, and provides a circuit with relay 307 by closing of contact 308-C thereby completing a stick circuit which comprises line wire L-1, terminal L-16, wire 153, terminal 154, wire 265, cam switch PM-15, wire 266, contact 308-C, bar 267, relay 308, bar 268, lower terminal of relay 307 and the above energizing circuit of said relay 307 to line wire L-2. Said circuit remains closed until it is opened by cam switch PM-15. Relay 307 upon being energized closes its contact 307-C, Fig. 20, which is inserted in a derived conductor 269 shunting the cam switch CF-1 and the contact R-126-B, thereby completing a circuit which comprises line wire L-1, terminal L-5, contact R_bBC, wire 133, shunt 269, contact 307-C, switch 135, relay 26-Mi, conductor bar 136, wire 137, cam switch CB-19, fuse F-18 and line wire L-2.

Energizing of relay 26-Mi of minor control causes, by providing operation of a fictitious automatic control, starting of the usual totalizing operations of the alphabetic and numeric printing tabulator.

It will be observed that cam switch PM-15 is set to maintain energizing of relay 308 during a time somewhat longer than one cycle, thereby providing a pair of total printing cycles of the tabulating machine.

On the other hand, energizing of relay 307 closes contact 307-A, thereby providing energizing of relays 306 and F by completion of the following circuit: line wire L-1, terminal L-11, bar 270, cam switch CF-22, cam switch CF-34, right-hand blade of contact 305-B, bar 271, wire 272, contact 307-A, wire 273, relay 306, contact 310-A, wire 264, wire 147, lower terminal of relay 305, wire 148, contact 301-A, lower terminal of relay 301, wire 149, switch 150, wire 152, fuse F-24 and line wire L-2.

Relays 306 and F are maintained by closing

of contact 306—BS which shunts contact 307—A till the end of the card feeding cycle which follows the progressive total, i. e., until contact CF—34 is opened. Energizing of relay 306 has for its object printing of progressive total without resetting the totalisers.

This is the operation of the relays 307 and 308 which have a triple function:

1. Provide operation of the totalizing mechanism of the tabulating machine by initiating a fictitious automatic control for printing of a progressive total on the end of one statement sheet and on the head of the following sheet.

2. Providing a pair of totalizing cycles of the tabulating machine.

3. Energize the relays 306 and F.

Besides relay 309 is energized by completion of a circuit which comprises line wire L—1, terminal L—16, wire 153, terminal 154, wire 180, contact Mi—11 (the central blade of which is in a position opposite to the position shown in Fig. 23 by reason of operation of the fictitious minor control), wire 181, contact 312—C, wire 182, double socket 183, plug connection 184, socket 185, wire 186, cam switch PM—17, wire 187, relay 309, cam switch CF—36, fuse F—20, and line wire L—2.

Therefore the clutch electromagnet E_m is energized by completion of a circuit comprising line wire L—1, terminal L—16, wire 153, terminal 154, wire 189, contact 309—A, contact 311—AS, wire 214, socket 275, plug connection 276, socket 277, contact 308—B, socket 277, plug connection 278, double socket 146, contact D—2 (normally closed), relay 304, 313, E_m with its contact 303—B, contact D—1 (normally closed), contact CB—35, wire 147, lower terminal of relay 305, wire 148, contact 301—A, lower terminal of relay 301, wire 149, switch 150, wire 152, fuse F—24 and line wire L—2.

Energizing of E_m causes starting of sheet 1 which will be fed by a pitch s_4^1 visible in Fig. 33, from the last line of the account to a predetermined location on the next account for printing of the progressive total 238.30. Said next account is lost, in order to avoid printing of said progressive total on an account intended to be sent to the customer. The end of the feed is defined by passage of perforation c_1 under the brush 201, as shown in Fig. 33, and said total is simultaneously printed on the account sheet and on the statement sheet.

It will be seen that feeding of the account sheet occurs between the effective initiating of automatic control and the proper printing of the total so that a blank sheet is in printing position as the progressive total is first printed.

Furthermore, it will be seen that during feeding of the account sheet contact 304—AI, Fig. 21, remains opened by reason of relay 304 being energized, thereby preventing any energizing of relay D—D' so that the paper feeding mechanism E_p is merely connected through the differential device D_1 to the upper roller 24 which drives the account sheet.

After the first printing of the progressive total the account sheet is fed by one line space during feeding of the statement sheet by the pitch s_2^2 . The sheets 1 and 2 are now in the positions shown in Fig. 34.

Feeding of the statement sheet is permitted by energizing of the relay D—D'. After the first printing of the progressive total the relay D—D' may be energized, first by reason of contact 304—AI being closed, as well as of contact

F—3 controlled by relay F, and afterwards by reason of closing of contacts C—3 and E—3 under the control of relays C and E.

As the abovedescribed energizing circuit of D—D' is completed, contact D—1 is closed, thereby causing energizing of the clutch electromagnet 117 of the platen roller 5.

Transmission of movement from the mechanism E_p is now switched through the anchor A of said differential device D_1 on the lower roller 5.

As soon as the clutch electromagnet E_m is energized, as has been shown hereinbefore, the statement sheet is fed by a pitch s_2^2 which is terminated upon perforation c_2 passing under the brush 207.

The automatic starting brush 208 has not caused the automatic starting relay 305 to be energized upon engagement thereof with the plate p_2 through perforation c_2 , by reason of contact F—2 being opened, said opening being due to energizing of relay F; the circuit of relay 305 includes indeed said contact F—2 by reason of the additional connections provided in order to permit printing of progressive totals by the device of the invention. Said circuit comprises line wire L—1, terminal L—16, wire 153, terminal 154, wire 189, plate p_2 , perforation c_2 , brush 208, terminal 240, wire 241, socket 242, plug connection 279, socket 280, contact F—2, socket 281, 30 plug connection 282, socket 244, wire 245, relay 305, wire 148, contact 301—A, lower terminal of relay 301, wire 149, switch 150, wire 152, fuse F—24 and line wire L—2.

As the record sheets are in the positions relatively to line T shown in Fig. 34, the second printing of the progressive total may be simultaneously effected on the statement and on the account intended to be sent to the customer.

After said second printing of the progressive total, relay D—D' is no more energized, contacts D_b—170, Fig. 22, of declutching electromagnet being opened; therefore the median blades of the contacts D—1 and D—2 are returned into their normal position shown in the drawings, contact D—1 is opened and interrupts the energizing circuit of the electromagnet 117 adapted to switch the drive from the paper feeding mechanism E_p to the upper roller 24.

The differential device being thus set, the account sheet is again fed by a pitch s_5^1 upon energizing of the clutch electromagnet E_m ; energizing of E_m is permitted by previous opening of contact 309—A under control of relay 309 the energizing circuit of which is completed as shown above. Feed s_5^1 is terminated when perforation c_1 passes under brush 201. Exactly in this moment the first line of the following account is in printing position, as shown in Fig. 35.

During said feed, the automatic starting brush 205 engages the plate p_1 through perforation c_1 at some lines in advance of the account end, thereby energizing the automatic starting relay 305 which is maintained energized by closing of its contact 305—B until its stick circuit is interrupted by the opening of cam switch CF—34. Contact 305—C is also closed upon energizing of relay 305 and cooperates with cam switch CB—36 to complete the energizing circuit of the clutch electromagnet C_{al} of the card feed mechanism, so that the cards may restart passing under the analyzer brushes of the tabulating machine.

After said feed s_5^1 of the account sheet, the statement sheet is fed by a double line space in this instance, to come into the position shown in Fig. 35.

In the foregoing were described the different feeding steps of the record sheets for printing of a progressive total.

Speed adjusting device of motor M.—It happens often that the device of the invention has to provide feeds of very small pitch; more particularly, when a customer number is changed at the last line of an account, the pitch by which the account sheet is to be fed to bring the line of the account on which the total is to be printed in printing position is approximately of $\frac{1}{8}$ in. and the inertia of the mechanism does not permit exact stopping registering with said line T.

For this purpose, an original device is adapted to control the speed of motor M to decrease it in the case of feeds of very small pitches, whilst maintaining the normal speed for feeds of normal pitch, said speed change occurring only upon operation of the automatic control of the tabulating machine.

Said device comprises the combination of said relays A the energizing of which is controlled by brushes 202 and 209 cooperating with the account sheet 1 and with the statement sheet 2 respectively, with a relay B adapted to be energized by starting of the automatic control upon change of a customer number or of an office number.

Referring now to Figs. 24 to 31 inclusive, more particularly to Fig. 24, and assuming for instance feeding of the account sheet, the brush 202 for energizing said relay A is arranged backward of the declutching brush 201 by a few line spaces to operatively engage its contact plate through the perforation c₁' of said account sheet when the latter is spaced by a few lines from the end of account.

Referring again to the main wiring diagram shown in Figs. 16 to 19 inclusive, the energizing circuit of said relay A, which is adapted to be completed by brush 202, comprises line wire L—1, terminal L—16, wire 153, terminal 154, wire 198, plate p₁, perforation c₁', brush 202, terminal 283, wire 284, relay A, wire 285, lower terminal of relay D', wire 217, fuse F—24 and line wire L—2.

Stick circuit of relay A comprises terminal 154, wire 170, contact D_b—170 of the declutching electromagnet D_b, wire 280, contact A—3 and relay A. Said stick circuit is completed by closing of contact A—3 upon energizing of relay A, and interrupted by opening of contact D_b—170.

Energizing of relay A causes opening of a contact A₁ which shunts a resistor 286 for adjusting the speed of motor M.

However, in spite of opening of contact A₁ the speed of motor M is not changed, said resistor being shunted by another contact B₁ normally closed. Said contact B₁ is opened only when a change of customer number or of office number occurs before the end of account. In this case, initiating of the automatic control energizes relays B by completion of a circuit comprising line wire L—1, terminal L—22, wire 287, cam switch CB—25, wire 288, three-blade contact M—4 (the median blade of which is in a position opposite to that shown in Fig. 18, by reason of relay 28—M₁ being energized under control of the tabulator minor control), wire 289, quadruple socket 286, plug connection 281, socket 282, wire 283, relay B, terminal 284, lower terminal of relay A, wire 285, lower terminal of relay D', wire 217, fuse F—24 and line wire L—2.

Relay B remains energized through its relay B' and a stick circuit completed by closing of contact B—2 under control of B, said stick circuit comprising line wire L—1, terminal L—16, wire

153, terminal 154, wire 170, contact D_b—170, wire 280, bar 281, contact B—2, relay B', bar 284, lower terminal of relay A, wire 285, lower terminal of relay D', wire 217, fuse F—24 and line wire L—2. Said stick circuit of B remains completed as the stick circuit of relay A until it is interrupted by opening of contact D_b—170, when said declutching electromagnet D_b is energized, thereby stopping the paper feed.

Energizing of relay B causes contact B—1 to be opened, and by reason of the previous opening of contact A—1 the resistor 286 is, this time, inserted in the energizing circuit of motor M, thereby decreasing the rotational speed thereof.

If the automatic control would become operative at the beginning of an account before perforation c₁' passes under the brush 202, relay B would be first energized to cause contact B₁ to be opened, but the motor would maintain its normal speed until relay A is energized by passage of perforation c₁' under brush 202. Thereupon contact A₁ would be opened to decrease the motor speed.

It results from the preceding that regardless of the sequence of energizing relays A and B and of the total length of paper feeding, the adjusting device of the invention provides feeding of the record sheet at a high speed on a great length and at a low speed on a small length, such as is represented by a few lines of the form, to always ensure correct positioning of the sheet.

Safety devices.—1. A pair of brushes 200 and 210 laterally spaced from the lines of brushes b₁ and b₂ are adapted to stop feeding of the account sheet or of the statement sheet respectively when the last form passes through the device of the invention, i. e., when there is no more paper under said brushes which now engage plate p₁ or plate p₂ respectively.

Stopping of the feeding mechanism E_p is caused by completion of energizing circuits of relay 301, which circuits comprise: for stopping the account sheet, line wire L—1, terminal L—16, wire 153, terminal 154, wire 198, plate p₁, brush 200, wire 286, plug 287, wire 281, relay 301, wire 149, switch 150, wire 152, fuse F—24, line wire L—2; and for stopping the statement sheet, line wire L—1, terminal L—16, wire 153, terminal 154, wire 198, plate p₂, brush 210, wire 288, plug 286, wire 287, relay 301, wire 149, switch 150, wire 152, fuse F—24 and line wire L—2.

Energizing of relay 301 causes opening of contact 301—A which interrupts the circuit of the clutch electromagnet E_m.

Brushes 200 and 210 are located with regard to the printing position T so that when the device of the invention comes to rest, there be at least one form under the platen roller, thereby permitting to engage other record sheets before restarting said device.

2. Another safety device which comprises substantially the combination of a pair of contacts D—8 and D—5 is provided in order to prevent the ordinary line by line paper spacing device of the tabulating machine from operating as the drive is switched from the paper feeding mechanism E_p to the platen roller.

The first contact D—8 is controlled by the clutch electromagnet E_m, and its opening causes the interruption of the circuit of the clutch electromagnet E_m of the ordinary paper spacing device of the tabulating machine as the paper feeding mechanism E_p starts rotating the platen roller after having been engaged by energizing of E_m.

However energizing of said clutch electromagnet E_m causes contact $D-9$ to be opened, regardless whether E_p drives the upper roller 24 or the platen roller 5.

Hence, the platen roller must be fed line by line in the case where the paper feeding mechanism E_p rotates the upper feeding roller 24. To this purpose, the second contact $D-5$ shunts the contact $D-9$ as shown in Fig. 16, and is controlled by relay D.

In this condition, as long as relay D is not energized, the differential device D_1 switches the movement of motor M through mechanism E_p to the upper roller 24 and contact $D-5$ remains closed, so that opening of $D-9$ upon energizing of E_m does not interrupt the circuit of the clutch electromagnet E_e of the ordinary paper spacing device of the tabulator.

However as soon as relay D is energized to rock the anchor A_1 of said differential device D_1 for switching the drive from mechanism E_p to said platen roller, it causes opening of contact $D-9$, and the energizing circuit of E_e is interrupted as contact $D-5$ is opened upon energizing of E_m .

3. In the preferred form of embodiment, there are provided additional safety contacts $D-8$ and $D-10$ adapted to be closed by energizing of said electromagnets D and E_m respectively, said contacts being serial mounted between plug 165 and one of the blades of contact 304-AS, as shown in Fig. 17. The function of said contacts is to prevent the device of the invention from operating in the case of a mechanical breakdown where the ordinary paper spacing device would become operative simultaneously with the mechanism E_p in spite of safety of contacts $D-5$ and $D-9$. Contacts $D-8$ and $D-10$ are indeed adapted to energize, by simultaneous closing thereof, relays 302 and 303, thereby operating the declutching electromagnet D_b to stop the drive.

While there is disclosed the fundamental novel features of the invention as applied to an alphabetic and numeric printing tabulating machine, it will be understood that various omissions, substitutions and changes in the form and details of the device illustrated and in its operation may be made by those skilled in the art without departing from the spirit of the invention.

More particularly, different connections provided on the switch board permit different operations to be carried into effect.

Starting and stopping of the record sheets may be effected either through brushes engaging their contact plates through perforations provided in very different locations of said sheets, or by means of contacts controlled by initiating of an automatic control or of a listing device, or upon printing of a major, intermediate, minor or progressive total.

The number and arrangement of the different rollers or feeding means may vary. The contact plates may be substituted for by any similar means, as for instance by contact rollers.

In a similar manner, the commutating means and the rocking anchor of the differential device may be suitably modified as to their form and operation.

It is the intention therefore to be limited only as indicated by the scope of the following claims.

What is claimed is as follows:

1. In an accounting machine including a printing mechanism for printing on first and second record strips with an interleaved carbon strip, a

- paper feeding device comprising a platen roller, said first record strip adapted to be operatively engaged by said printing mechanism for printing thereon an account, said second record strip engaging said platen roller for printing thereon a statement, said record strips including a marginal series of longitudinally spaced perforations, said perforations being located with respect to the positions in which it is desired to start and stop printing on said strips, a feed roller for feeding said account strip, a plurality of analyzer brushes, a plurality of contact plates, said record strips being arranged between said analyzer brushes and said contact plates for operative engagement of said contact plates by said analyzer brushes through said perforations, means for frictionally engaging said rollers with said record strips for movement of said account strip with said feed roller and of said statement strip with said platen roller, a differential device adapted to selectively drive said platen roller and feed roller, an anchor member adapted to control said differential device, electromechanical means adapted to control said anchor member, a driving means, a line by line spacing device adapted to be driven by said driving means, a paper feeding means adapted to be driven by said driving means and to feed said record strip by a variable pitch, a plurality of cam switches under control of said accounting machine and a plurality of circuits with electrical controls in said feeding means adapted to cooperate with said analyzer brushes and cam switches for automatic control of the electrical controls of said feeding means for starting, feed and stopping of said record strips.
2. In a machine for feeding record sheets, a feed roller for one sheet, a platen roller around which both sheets are passed, means for driving said rollers, shafts located near said rollers, friction feeding means on said shafts comprising frames carrying pairs of feed rollers with interspersed gears, said gears meshing with gear trains connected to said platen roller and feed roller respectively, and a plurality of spring members adapted to urge said feed rollers into engagement with said platen roller and feed roller respectively.
3. A paper feeding device as claimed in claim 1 and comprising an analyzer brush adapted to sense the perforations located with respect to the end of the statements, a plurality of relays under control of said analyzer brush, a cam switch, a plurality of contacts under control of said relays, and another relay adapted to be energized by operation of said cam switch and contacts and to control said anchor member.
4. A paper feeding device as claimed in claim 1 and comprising a plurality of gears adapted to mesh with each other for operatively connecting said platen roller to said differential device, and a free wheel device including a ratchet wheel rigid with said platen roller and a pawl rigid with one of the extreme gears of said plurality of gears, said pawl cooperating with said ratchet to drive the platen.
5. A paper feeding device as claimed in claim 1 and comprising a carbon paper roller to which said carbon strip is connected, driving connections between said roller and said platen, whereby said carbon strip is adapted to be driven from said platen roller with speed reduction.
6. A paper feeding device as claimed in claim 1, wherein said differential device includes a planet wheel carrier, a first gear system operatively connecting said planet wheel carried to said platen roller, a pair of planet wheels journaled in said

planet wheel carrier and adapted to mesh with each other, one of said planet wheels connecting said planet wheel carrier to said paper feeding means, a second gear system and a pinion mounted for idling and adapted to mesh with said other planet wheel for operative connection of said planet wheel carrier with said feed roller through said second gear system and said idler pinion, said anchor means serving to make effective either the first or second gear system to operate the platen roller or feed roller.

7. A paper feeding device as claimed in claim 1, wherein said differential device includes a planet wheel carrier, and comprising a shaft adapted to be driven from said paper feeding means and a pinion rigid with said shaft, said anchor member comprising a pair of axially spaced arms, the first of said arms being adapted to engage said pinion upon energizing of said electromechanical means and the other of said arms being adapted to stop said planet wheel carrier upon de-energizing of said electromechanical means.

8. A paper feeding device as claimed in claim 1 and comprising a clutch electromagnet for said paper feeding means, an energizing circuit for said clutch electromagnet and a contact adapted to be engaged for closing by said anchor member upon energizing of said electromechanical control means and to complete said energizing circuit of said clutch electromagnet.

9. A paper feeding device as claimed in claim 1, wherein said paper feeding means comprises a clutch device between the driving means and the feeding means, a first electromagnet for engaging said clutch device, a second electromagnet for disengaging said clutch device, said electromagnets being operated under control of impulses through said analyzing brushes, and a plurality of gears adapted to mesh with each other and to operatively connect said paper feeding means with said differential device.

10. In a machine for feeding paper, a driving means, a line spacing device comprising a notched disc, a first ratchet wheel, a first pawl, said notch disc being adapted to be driven from said driving means through said ratchet wheel and pawl, an electromagnet adapted to cooperate with said pawl for controlling starting and stopping of paper feed, a crank pin rigid with said notch disc, a link member pivotally connected to said crank pin, a second pawl pivotally connected to said link member, a second ratchet wheel adapted to cooperate with said second pawl, a brake for said second ratchet wheel, a pin rigid with said second pawl and a cam disc adapted to be operatively engaged by said pawl pin and to drive said differential device the angular position of said cam disc being adjustable for varying the number of line spaces.

11. In a machine for printing data on strips divided into forms, a paper feeding device as claimed in claim 1, wherein said marginal perforations are located with respect to the first line of the forms, said analyzer brushes are adapted to sense the printing position of a form and means controlled thereby to control starting and stopping of said paper feeding means to bring the first line of the next form in printing position.

12. In a card controlled tabulating machine comprising a card feed mechanism, a paper feeding device as claimed in claim 1, wherein some of said analyzer brushes are arranged to sense a stop control perforation before it reaches a related feed control analyzing brush and for sens-

ing said perforations shortly before the end of paper feed, and comprising a relay adapted to cooperate with said analyzer brushes, said relay cooperating with said mechanism to initiate upon energizing thereof starting of said card feed mechanism.

13. In a card controlled tabulating machine comprising a card feed mechanism and automatic group control mechanism, a paper feeding device as claimed in claim 1, wherein some of said analyzer brushes are arranged for sensing said perforations shortly before the end of paper feed, and comprising a relay adapted to cooperate with said analyzer brushes and to initiate upon energizing thereof starting of said card feed mechanism, and a plurality of contacts operated by said group control mechanism adapted to prevent energizing of said relay, whereby operation of the card feed mechanism is suspended by operation of the group control mechanism.

14. In a tabulating machine comprising an automatic group control mechanism, a paper feeding device as claimed in claim 1 and comprising, in combination, a pair of relays and electrical controls operated by said relays for controlling the speed of said driving means, the first of said relays being adapted to be controlled by said automatic group control mechanism and the second of said relays being adapted to be controlled by said analyzer brushes, whereby the speed of the driving means is reduced upon a group change and before the feeding means is stopped under control of a perforation.

15. In a machine as claimed in claim 1 with the printing mechanism printing on a third record strip under a carbon strip for printing therein in duplicate and having paper feeding means comprising a counter feed roller for feeding said duplicate strip, an oscillating pinion carrier, a pair of pinions journaled in said pinion carrier, a first gear rigid with said platen roller, a second gear rigid with said feed roller and a third gear rigid with said counter feed roller, said pinion being adapted to mesh, in one of the positions of said oscillating pinion carrier, with said first gear and said third gear thereby operatively connecting said counter feed roller with said platen roller, and in the other position of said oscillating pinion carrier, with said second gear and said third gear thereby operatively connecting said counter feed roller with said feed roller.

16. In a tabulating machine with minor, intermediate and major group control devices including minor, intermediate and major control relays, wherein energizing of the major control relay causes automatically energizing of the intermediate and minor control relays, a paper feeding device as claimed in claim 1 and comprising a first plug connection for mounting said minor control relay in parallel with said intermediate control relay, a socket associated with and electrically separated from said intermediate control relay, a brush adapted to sense a perforation located with respect to the end of the account sheet, a double socket connected, on the one hand, to said electrical controls for said paper feeding means, and on the other hand, to said brush, and a second plug connection for connecting said intermediate control socket with said double socket, whereby feeding is initiated either by group change or by sensing the end of a sheet.

17. In a machine for printing on three record strips with interleaved carbons, a driving means, strip feeding means, a feed roller for one record strip, a feed roller for the second record strip,

means for connecting either of said rollers to said feeding means, a feed roller for the third strip, and means for selectively connecting the last mentioned roller to be driven by either of the other two rollers.

18. In a card controlled machine with card feeding and sensing means to control printing on a record web bearing feed control perforations, a driving means, web feeding means, means for connecting said feeding and driving means, means for disconnecting said feeding means from the driving means, a sensing brush in the path of said indicia, means under control of said brush when an indicium is sensed for operating said disconnecting means for stopping the web feed, a second sensing brush in the path of said indicia and located in front of the first mentioned brush to detect an indicium before the first mentioned brush, and means under control of said second brush when an indicium is sensed for initiating operation of said card feeding means.

19. In a card controlled machine with group control devices and adapted to print upon a record web having feed control indicia, a driving means, a web feeding means, means for connecting said feeding and driving means, means for sensing said indicia, means under control of said

sensing means for controlling operation of said connecting means when a indicium is sensed, a total printing means, means under control of said group control devices for initiating operation of said total printing means, and means under control of said sensing means for initiating operation of said group control devices for causing total printing upon detection of a feed control indicium, whereby said group control devices serve a dual role in causing total printing upon sensing of a feed control indicia and causing total printing upon a change in card groups.

20. In a card controlled machine with group control devices and adapted to print upon a record web having feed control indicia, a driving means, a web feeding means, means for connecting said feeding and driving means, means for sensing said indicia, means under control of said sensing means for controlling operation of said connecting means when an indicium is sensed, a motor for said driving means, means for changing the speed of said motor, and means under joint control of said group control devices and said indicia sensing means for calling said speed changing means into operation.

IOINO GHERTMAN.
